BUILDING BLOCK

Earl R. Brenneman and Earl Swett, Alma, Mich.

Application August 3, 1942, Serial No. 453,346

5 Claims.

(Cl. 72—43)

This invention relates to cementitious blocks, particularly useful in house or other building. It is a primary object and purpose of the present invention to provide a building block having an outside strong and weather resisting composition and an inner side of gypsum material of softer composition and one which is capable of being worked, have nails or the like driven thereto, which can be sawed across to remove parts thereof when necessary and against the inside surface of which an inside finish may be applied which will firmly adhere. The two members of the block of separate and distinct materials are spaced from each other and tied together by separable connecting ties, which ties may be assembled with the block parts on the job, the blocks not requiring complete building up and assembly thereof until they are to be used. This enhances ease and reduces cost of transportation as the disassembled block members occupy less space than the assembled block.

With said blocks having the inner and outer members thereof connected together and held by a plurality of cross ties a wall laid using the blocks is provided with an interior dead air space of value in heat insulation. Moreover, the ties can be sawed away in part when necessary after the wall is laid for the passage of wiring, pipes, or conduits should the ties be in the way; and if prior to laying the wall it is known where said pipes, conduits and the like are to pass certain of the ties in a block may be omitted, there being in a complete block a plurality of said cross tie members in excess of those required for all blocks in a wall so that the removal or omission of a part of them does not endanger or depreciate the strength of the wall.

A further feature of the invention is the positioning of the cross ties inwardly from the upper and lower sides and from each end of the block a predetermined distance such that when a wall is laid the upper row or tier of blocks may have applied thereto a plate which will fit in between the upper edge portions of the inner and outer members of the blocks and will rest upon the uppermost cross ties thereof having its upper surface substantially flush with the upper edges of the upper row of blocks. Also for window and door openings there will be provided the properly dimensioned spaces to receive vertical side members and upper and lower members, the inner faces of which will be substantially flush with the edges of the blocks at said openings and with which a window and door frame may be suitably connected. The blocks also are readily fashioned

for turning corners by merely cutting away a part of the inner block members at the corners which can be readily done on the job, requiring no special corner block constructions.

5 To these ends and others which will appear, we have produced the novel building block, an understanding of the construction and use of which may be had from the following description taken in connection with the accompanying drawings, in which,

Fig. 1 is a perspective view of a building block made in accordance with our invention.

Fig. 2 is a transverse vertical section therethrough.

15 Fig. 3 is a longitudinal vertical section between the inner and outer members of the block.

Fig. 4 is a longitudinal horizontal section substantially in the plane of one of the series of cross tie members.

20 Fig. 5 is a fragmentary illustration of a wall laid using said blocks and illustrating the top plate at the upper edge of the wall and a window or door opening therein lined with frame members inset in the blocks around said opening.

25 Fig. 6 is a fragmentary section and end elevation at the upper part of the wall.

Fig. 7 is a fragmentary plan view illustrating one form of corner, and

30 Fig. 8 is a similar view illustrative of a modified form of corner which may be used.

Like reference characters refer to like parts in the different figures of the drawings.

In the construction of the block an outer member 1 of rectangular parallelepiped form is made from a hard weather resisting cementitious material. In practice we have used cindercrete, that is, a cementitious composition in which the aggregate is principally of cinders, but it is to be understood that other aggregates may be used such as sand, gravel and the like as in ordinary concrete. The binder used will be preferably Portland cement.

The inner block member 2 is also of rectangular parallelepiped form but of a narrower thickness.

45 It will be of a gypsum composition and at its inner side may be provided with the usual fluted or roughened surface for the application of plaster or other finishing at the inside when the blocks have been assembled.

The inner and outer block members 1 and 2 are formed with a plurality of elongated openings 3, circular in cross section, reaching entirely through the block members from their upper to their lower sides. Said block members 1 and 2 are also provided with a plurality of series of

transverse openings (not numbered) which extend partly through the blocks and which connect with the vertical openings 3 at a side thereof as shown. When the two block members 1 and 2 are assembled these horizontal openings are in horizontal alignment in the two block members and will have open ends at the sides of the block members adjacent each other, the other sides of said block members being smooth and unbroken as said horizontal openings do not pass through said members.

In practice, as shown, there are four of the vertical openings 3 in each of the block members 1 and 2 spaced from each other and there are two series, an upper and a lower series of four horizontal openings each, the openings in each horizontal series being in horizontal alignment. This will provide for the use of eight cross tie members between the inner and outer cementitious block members, which of course may be varied without departing from the invention.

The cross tie members, preferably of wood, though other materials of an equivalent nature may be used, include an intermediate section 4 which as shown is square in cross section, the length of which governs the spacing of the block members. From each end of the intermediate section 4 a spindle 5 of cylindrical form and of a reduced diameter is provided integral with the central section. Each of the spindle members 5 between its ends is formed with a continuous annular groove 6 of concave form as shown.

The spindles 5 are inserted in the horizontal openings in the block members 1 and 2 and the grooves 6 come into direct conjunction with the vertical openings 3 in the block. Dowels 7 preferably of wood are passed through the openings 3 and are partially received in the grooves 6 thereby locking the cross ties in place and holding the block members 1 and 2 in secure relation to each other.

It is to be noted that the tie members are located a prescribed distance below the upper edge, above the lower edge and with the end edges of the block. This distance is substantially equal to the standard thickness of an ordinary 2" x 4" while the length of the central portions 4 of the tie members is slightly in excess of the standard width of said 2" x 4". Thus when there has been laid a wall of the blocks a plate 8 of the standard 2" x 4" dimensions when planed may be laid upon the uppermost horizontal tie members as shown in Figs. 5 and 6 for the connection of the necessary building members such as plates or the like which will support the rafters of the roof. Likewise at window and door openings vertical frame members 9 and horizontal members 10 may be inset into the blocks until stopped by the tie members 4, this providing a frame to which a window or door frame may be secured.

The blocks shown in Fig. 1 may be made in one-half the length there shown to provide blocks, as indicated at 1a in Fig. 5, for the proper breaking of joints in laying the wall. At a corner, as shown in Fig. 7, parts of the inner block members 2 will be cut away at one end of the block so as to reduce the length of the inner block members and prevent placing them in relation to each other as indicated at 2a in Fig. 7. Of course, as shown in Fig. 8, one only of the corner blocks may have its inner block member shortened as indicated at 2a and the other corner block laid with relation thereto as indicated in said Fig. 8.

The inner space in the wall may be used to house pipes, wiring and conduits of various char-

acters. We have shown in Fig. 8 a pipe 11 indicated as passing vertically through such space in a wall; and at the places where the passage of the pipe would be interfered with by the cross ties, said ties have been removed sufficiently for the pipe passage by sawing the ties across for such removal. The passage of electric wiring at said inner insulating spaces may be done without removing any of the ties.

While the central section 4 of a cross tie is shown as square in cross section it is evident that it may be of a cylindrical form having a diameter equal to a side of the square section shown in Fig. 3. The interlocking connection of the cross ties and the locking dowels 7 permits a rotation of the cross ties 4 if necessary to bring their upper and lower surfaces into horizontal planes and their side surfaces into vertical planes so as to properly receive the members 8, 9 and 10 and back them up with a sufficiently solid backing.

From the foregoing it will be evident that the block members 1 and 2 may be separately cast, the cross ties provided, the parts shipped in disassembled relation and the blocks assembled at the place where a wall is to be laid. The outer block members 1 of cindercrete, concrete or the like, exposed to the weather will be able to withstand all weather conditions the same as ordinary cindercrete or concrete building blocks. The inner block members 2 are protected from the weather. Said inner block members may be readily cut to shorten them when necessary as at the corners, are adapted to have nails driven thereinto and to carry the inner finishing coatings in a room such as plaster, paint or the like, may if necessary support lath to which plaster may be applied. The outer block members 1 will prevent the passage of moisture through the wall and the continuous space between the inner and outer parts of a laid wall furnish the best type of insulation against passage of heat, making a building constructed of said blocks economical to keep in a heating condition in cold weather and cooler in warmer weather.

The building blocks described are not only useful for building walls but may be used for floors and partitions and are of value in foundations. For partitions both block members would be of the gypsum cementitious composition or equivalent and in floors the spaced block members may be of the same composition. For foundations the blocks may be laid to the desired height of the foundation and then the spaces between the inner and outer members of the blocks filled with concrete, eliminating the necessity for building forms which have to be removed after a concrete foundation has been poured.

It is further evident that if it should be desirable that any part of a wall, at the corners or any other part thereof, may be reinforced by vertical concrete posts or pilasters. For example at a corner, as in Fig. 7, locating a board vertically against the spacers 4 would provide an enclosing form for receiving concrete which would be held therein until set. Also at other places than the corners vertical posts or pilasters may be provided with a removal of such tying spacing members as might be needed by sawing across at the juncture of the spindle ends thereof at the larger and intermediate portions of said spacers and ties.

This construction of block also lends itself effectively to making finished blocks of different widths by merely utilizing different lengths of spacing and tie members, the length of the inter-

mediate sections 4 of which may be varied. This is an item of very appreciable economy, wider cementitious blocks as now generally made rapidly increasing in cost as compared to narrower ones and having increased transportation costs because of greater weight. The use of same dimensions in inner and outer block members in making a wider block by utilizing different lengths of intermediate portions for the spacing and tying members increases the cost of the wider blocks but little. And the reinforcement of the wider block walls by concrete posts or pilasters at spaced intervals in the length of a wall readily takes care of any desired increase in strength of the wall.

The block is particularly valuable from a practical utility standpoint and has been produced with such ends in view.

The invention is defined in the appended claims and is to be considered comprehensive of all forms of structure coming within their scope.

We claim:

1. A building block comprising an outer block member of rectangular parallelepiped form and of a hard weather resisting cementitious material composition, an inner block member of the same form of a softer material, each of said block members having a plurality of spaced cylindrical openings therethrough paralleling the vertical sides of said block members, a plurality of tie members each having an intermediate portion and a spindle at each end thereof of cylindrical form projecting from the intermediate portion and having a cross sectional area less than that of the intermediate portion of the tie members, and each of said spindles between its ends having a continuous annular concave groove therein, said block members having openings for the reception of said spindles, said last mentioned openings and the vertical openings in the block members intersecting each other, and elongated dowels of a size and shape to be passed into and through the vertical openings in the block members, the positioning of the spindle receiving openings and the dowel receiving openings being such that said dowels seat at one side in portions of the grooves in said spindles, as specified.

2. A building block comprising an outer block member of rectangular parallelepiped form and of a hard weather resisting cementitious composition, an inner block member of the same form, upper and lower series of tie members adapted to be associated with and located be-

tween said block members, each of said tie members having an intermediate section of predetermined length to govern the spacing of said block members from each other, and each of said tie members having a spindle at each end of less cross sectional area than the cross sectional area of said intermediate portion, said block members having openings each in one side thereof for the reception of said spindles, means insertable into said block members to engage with and interlock with said spindles, the upper series of said tie members being located below the upper edges of said block members each a predetermined distance and the lower members of said tie members being located above the lower edges of said block members the same distance, as specified.

3. A building block containing the elements in combination defined in claim 2, each of the end tie members of each of said upper and lower series of tie members being located inwardly from each end of the block a predetermined distance.

4. A building block containing the elements in combination defined in claim 2, each of the end tie members of each of said upper and lower series of tie members being located inwardly from each of the ends of the block members a predetermined distance, said distance being equal to the distance that said upper and lower series of tie members are respectively located below and above the lower and upper edges of said block members.

5. In a building block inner and outer block members adapted to be located in spaced relation with adjacent sides in vertical planes spaced from each other, said block members at said adjacent sides having a plurality of horizontal openings partially therethrough and said block members having vertical openings from their upper to their lower sides intersecting said horizontal openings, spacing and tie members located between the blocks each having an intermediate portion and a spindle at each end thereof of less cross sectional area, said spindles being adapted to be received in said horizontal openings in said block, each of said spindles having a continuous annular groove therearound, and elongated dowels passing through the vertical openings in said block members and seating in said grooves of the spindles, as specified.

EARLE R. BRENNEMAN.
